UNITED STATES PATENT OFFICE.

JONAS POFFENBARGER, OF FARMERSVILLE, OHIO.

IMPROVEMENT IN CARRIAGE-TOP SETTERS.

Specification forming part of Letters Patent No. **143,183**, dated September 23, 1873; application filed April 5, 1873.

To all whom it may concern:

Be it known that I, JONAS POFFENBARGER, of Farmersville, in the county of Montgomery and State of Ohio, have invented a new and valuable Improvement in Carriage-Top Setters; and I do hereby declare that the following is a full, clear, and exact description of the construction and operation of the same, reference being had to the annexed drawings making a part of this specification and to the letters and figures of reference marked thereon.

Figure 1 of the drawings is a representation of a side view of my invention. Fig. 2 is a front view of the same. Fig. 3 is a sectional view of the same.

This invention has relation to means for setting carriage or buggy tops; and it consists in the construction and novel arrangement of devices constituting an adjustable gage-frame and plumb for this purpose, with an arc and curved slot, as hereinafter described.

In the accompanying drawings, the letter A designates the side standards, which, when in use, are designed to be clamped on the buggy-seat. These standards are connected by the foot-board h and the transverse bar k. B indicates the segment-boards, which are pivoted by means of screws a to the side standards A, and the pivot-screws pass through slots b in the segment-boards, whereby provision is made for adjusting the height thereof. The segment-boards are connected by the transverse bars C, and are provided with the adjustable slides D, whose position is regulated and fixed by means of suitable slots e and clamp-screws d. The angular position of the segment-boards is regulated by the adjustment of the arcs E. These are provided with curved slots v and clamp-screws w for

fixing the adjustment. Each segment-board should be provided with a spirit-level, as indicated at s on the drawings. A similar level is designed to be used, when required, in connection with the transverse bar k. Plumb-bobs m are connected with the rear end of each segment-board.

In using the setting-instrument, place the upright portion or standards on the buggy-seat and secure the same by clamping or otherwise. Level the segment-boards by means of the spirit-levels. Let down the plumb-bobs to ascertain the slant desired for quarters. The slides D are then to be raised against the rounds or bows of the top and secured in position by means of the clamp-screws. The height of the top can be regulated by adjusting the segment-boards up or down. If the top is desired to droop, the proper degree of slant can readily be given by means of the adjustable arc-braces E.

This description and the drawings relate to a setter for buggy-tops. For setting carriage-tops the instrument is made in a similar manner, but extra segment-boards are required.

What I claim as new, and desire to secure by Letters Patent, is—

The pivoted segment-board B, with the arc E and curved slot v, with or without a spirit-level and plumb-bobs, substantially as shown and described.

In testimony that I claim the above I have hereunto subscribed my name in the presence of two witnesses.

JONAS POFFENBARGER.
